UNITED STATES PATENT OFFICE

152,848

DESIGN FOR A COIN DISPENSER

Frederick A. Wetherill and Walter P.
Staniszewski, Middletown, Mass.

Application April 9, 1947, Serial No. 138,258

Term of patent 3½ years

(Cl. D52—4)

To all whom it may concern:

Be it known that we, Frederick A. Wetherill and Walter P. Staniszewski, residing at Middletown, in the county of Middlesex, and State of Connecticut, have invented a new, original, and ornamental Design for a Coin Dispenser, of which the following is a specification, reference being had to the accompanying drawing, forming part thereof.

The left side of the front of the coin dispenser is identical to the right side of the front.

We claim:

The ornamental design for a coin dispenser, as shown and described.
